UNITED STATES PATENT OFFICE.

LEWIS C. MYERS, OF NEW YORK, N. Y., ASSIGNOR, BY MESNE ASSIGNMENTS, TO
ROYAL TYPEWRITER COMPANY INC., OF NEW YORK, N. Y., A CORPORATION OF
NEW YORK.

TYPE-WRITING MACHINE.

1,092,380.

Specification of Letters Patent. Patented Apr. 7, 1914.

Application filed April 22, 1909. Serial No. 491,547.

To all whom it may concern:

Be it known that I, LEWIS C. MYERS, a citizen of the United States of America, residing in the borough of Brooklyn, city and 5 State of New York, have invented certain Improvements in Type-Writing Machines, of which the following is a specification.

This invention relates to a novel form of card holder or clamp applied to a front 10 strike visible machine such, for instance, as the Royal Standard.

It comprises a card holding plate detachably mounted in or upon the machine between the surface of the platen and the 15 usual vertically vibrating ribbon guide. This card holding plate is constructed and located in such way as to hold the card at the printing point against the platen so that printing may be impressed upon the 20 card close to any of its edges.

In the accompanying drawings: Figure 1 is a front elevation showing the platen, paper feed and clamping devices, etc., and my improved card holder: Fig. 2, a top plan 25 view of what is shown in Fig. 1: Fig. 3, a side elevation showing some of the shafts in section: Fig. 4, a front elevation of the card guide detached: Fig. 5, a detail view showing one way in which the card guide 30 may be used: Fig. 6, a similar view indicating the feeding of a card in full lines and the final passage of the card from the platen in dotted lines: Fig. 7, a like view showing a card with its lower edge substantially at the 35 printing line: Fig. 8, a detail view showing one corner of the card holder plate provided with a socket for receiving a vertical pin at the end of the segment plate: Fig. 9 is a front elevation, and Fig. 10, a side elevation of the 40 type bar guide: Fig. 11, an end elevation: and Fig. 12, a front elevation of the modification, of the card clamp, that is indicated in Fig. 8.

The drawings show a paper table *a*, paper 45 pan *b*, rear feed rolls *c*, front feed rolls *d*, vertically movable scale *e* that may be moved up to the line of print when the feed rolls are thrown off. The feed rolls are thrown away from the platen and the scale 50 bar moved to the printing point when shaft *f* is partially rotated, the pivoted arms or levers carrying the feed rolls normally lie in transverse notches in the shaft and when the shaft is rotated they are forced up on 55 the high part, that is to say, upon the pe-

riphery of the shaft and the feed rolls are then withdrawn from the platen.

g is a rotatable shaft operated through the release lever (not shown) to move the scale bar to the printing point at the time 60 the feed rolls are thrown off,—that is to say, *g* is a rock shaft having a forwardly projecting curved arm *g'* at each end and to the ends of which are pivoted upwardly extending arms *g''* in the upper ends of which 65 is carried the scale bar *e*.

h are hinged top clamps or guides extending forward from the rear over the platen and capable of being thrown rearwardly out of operation as indicated by dotted lines 70 in Fig. 3. Other paper clamps *i* are also shown.

j is the segment that has at each of its ends an aperture *j'* to receive pins *k* at the lower corners of the vertically disposed card 75 clamps or guide *l*: or, as shown in Fig. 8, the card clamp or guide *l* may be formed with sockets *k'* to receive pins *j''* extending up from the segment.

m indicates a well known form of type 80 bar guide and *n* a well known form of ribbon vibrator located in rear of the guide.

Between the printing surface of the platen *o* and the rear of the ribbon vibrator is located the card holder *l* that may be appropriately mounted in any suitable way upon the machine, as, for instance, in the ways shown in Figs. 1 and 8.

On the lower plate of the type bar guide at each end or side thereof is an upright projection *p* that may be turned inwardly or rearwardly sufficient to bear against the lower edge of the card holder *l* and hold it out of contact with the ribbon vibrator.

The card holder is shown detached in Fig. 95 4 in front elevation and in top plan in Fig. 2. It comprises a flat plate to which the letter *l* has been applied. Its upper edge has in it an oblong recess *q* of suitable width and of sufficient depth to accommodate the 100 type bar heads;—that is to say, to permit the type to make impact against the platen. To the right and left of this opening *q*, the plate is formed with openings *r*, *r*, which are preferably triangular in shape, as shown, or otherwise, and the plate at the straight bottom edges of these openings is engraved with a scale *s*. The small tongues or projections *t* formed of the sheet metal of which 105 the card holder plate is formed and project- 110

ing into the openings r , serve to prevent an inserted card envelop or sheet from entering either of the openings or striking against the edges or walls thereof. The metal forming the edges of the openings r is thrown out as indicated at r' to stiffen the plate and form rounded rear edges that will not tend to hold or impose any drag upon the card as it is passed around the platen. 10 Beyond the flat central portion of the plate having the openings r , r , the plate is formed with lateral extending wings u that are deflected to the front as seen in Fig. 2, the point of deflection or bend being indicated 15 by the line u' in Fig. 4. The manner in which such a card holder will control the card at the printing point is indicated, for instance, in Fig. 5, where v represents a card that has been fed around the platen and has 20 been allowed to pass up vertically therefrom instead of under the top roller clamps h' . In such case the rollers h' serve as a back guide for the card while the card holder 25 serves as front guard. Fig. 7, shows a card leaving the platen in the ordinary way under the clamp rolls h' . The apertures or openings r allow inspection 30 of the printed matter upon the card and also facilitate alining of the card by the operator. The forwardly obliquely disposed wings u 35 serve to guide the card into position if it be introduced either under the platen or backwardly over the top of the platen to one side of the central part of the card holder (Fig. 6) so that when the carriage moves laterally, the card will pass accurately behind the central part of the card holder and be held closely against the platen.

The clamping rollers h' Figs. 1, 2 and 3,

act to hold a card from above so that its 40 lower part, that is pressed against the platen by the holder l , may be printed upon close to the bottom edge. When required these rollers may be thrown back out of the way as indicated in Fig. 3. 45

I claim:

1. A card guide adapted to be mounted between the ribbon vibrator and the printing surface of the platen of a front strike typewriting machine, comprising a flat plate 50 with a recess opposite the printing point on the platen through which the types impact against the platen, apertures on each side of said recess having straight bottom edges engraved with a scale and forwardly obliquely 55 disposed side wings for deflecting an inserted card into position between the central flat part of the plate and the printing surface of the platen.

2. A card guide adapted to be mounted 60 between the ribbon vibrator and the printing surface of the platen of a front strike typewriting machine, comprising a flat plate with a recess opposite the printing point on the platen through which the types impact 65 against the platen, apertures on each side of said recess having straight bottom edges engraved with a scale and also having at said bottom edges tongues projecting into the openings to prevent an inserted card from 70 engaging the edges thereof.

In testimony whereof, I have hereunto subscribed my name.

LEWIS C. MYERS.
